UNITED STATES PATENT OFFICE

118,682

DESIGN FOR A GAME BOARD

Victor D. Keller, Coffeyville, Kans., assignor of one-half to Marion C. Hayes, Caney, Kans.

Application July 7, 1939, Serial No. 85,868

Term of patent 7 years

To all whom it may concern:

Be it known that I, Victor D. Keller, a citizen of the United States, residing at Coffeyville, in the county of Montgomery and State of Kansas, have invented a new, original, and ornamental Design for Game Boards, of which the following is a specification, reference being had to the accompanying drawing, forming part thereof.

The figure is a plan view of a game board, showing my new design.

The article is of no appreciable thickness and the game features are flush with the surface. The small circles indicate holes through the board. The small areas or zones are lined to indicate contrasting colors.

I claim:

The ornamental design for a game board, as shown and described.

VICTOR D. KELLER.
